UNITED STATES PATENT OFFICE.

ARTHUR WAINER, OF HAVERFORD, PENNSYLVANIA, ASSIGNOR TO R. H. BEAUMONT
CO., OF PHILADELPHIA, PENNSYLVANIA, A CORPORATION OF DELAWARE.

TRAM-CAR EQUIPMENT.

Application filed February 5, 1926. Serial No. 86,125.

The principal object of the present invention is to provide an improved construction and arrangement whereby the shock occurring when car gate rollers meet the dumping 5 cams is minimized and absorbed by the cams. Another object of the invention is to provide for properly opening the gates of cars having comparatively large longitudinal dumping openings. These gate structures 5 and 6 are movable crosswise of the direction of motion of the car. For this purpose they are pivoted on an axis 7 ranging in that direction. The gate structures 5 and 6 are shown as of the variety which close by gravity and they are therefore self-closing. The dumping cam structure happens to be mounted upon a movable frame 8 carried by rollers 9 in order that the dumping point can be shifted on the

10 Other objects of the invention will appear from the following description at the end of which the invention will be claimed. 65

15. Stated in general terms, the invention may be said to comprise a tram car provided with a dumping gate structure movable crosswise of the direction of motion of the car and a dumping cam having a working face generally inclined to the perpendicular and of which a part is substantially straight and arranged at high level and of which a part is warped and extended downward and inward toward the middle of the tramway. The dumping cam is therefore operative crosswise of the tramway and it may be said to be of the general form of a parallelogram having a wedge 75

The invention also comprises the improvements to be presently described and finally 25 claimed.

20 claimed. Referring to the drawings forming part thereof— It is well to bear in mind that the amount of opening movement of the gate structure is large because the opening in the bottom of the car should be large for quick and ready discharge and because with a large opening the side walls may be steep providing 80

Figure 1 is a side view with parts broken away and of somewhat diagrammatic character of tram car equipment embodying features of the invention. 85

Fig. 2 is an end view, partly in section of the same showing two gates.

Figs. 3 and 4 are a plan and an elevation of the dumping cams shown in Fig. 2.

Fig. 5 is a view similar to Fig. 2 showing a single gate.

Fig. 6 is a view similar, so far as it goes, to Fig. 5 showing two gates geared to-

Fig. 7 is a view similar to Fig. 2 showing modification of the gate structure in which

Fig. 8 is a view similar to Fig. 7 showing a modification of the gate structure in which there is a single gate.

Fig. 8 is a view similar to Fig. 7, but showing two gate structures, and Fig. 9 is a view of a tram car having a

Referring to Figs. 1 to 4, 1 is a tramway

upon which the car 2 travels. The car 2 is provided in its bottom with a dumping opening provided by inclined side walls 3 and straight or vertical end walls 4. 5 and 6 are gates or gate structures adapted to cover and uncover the dumping opening in the car

These gate structures 5 and 6 are movable crosswise of the direction of motion of the car. For this purpose they are pivoted on an axis 7 ranging in that direction. The gate structures 5 and 6 are shown as of the variety which close by gravity, and they are therefore self-closing. The dumping cam structure 8 happens to be mounted upon a movable frame 9 carried by rollers 9 in order that the dumping point can be shifted, or the dumping cam might just as well be mounted on a fixed structure. The dumping cam has its high part or working face disposed at an angle or inclination to the vertical or perpendicular. A part or portion of this face 10 is substantially straight and arranged at a high level and a portion 11 is warped and extends downward and inward toward the middle of the tramway. The dumping cam is therefore operative crosswise of the tramway and it may be said to be of the general form of a parallelogram having wedge shaped ends. 12 are cam rollers with which the gate structures 5 and 6 are equipped and with which the dumping car cooperates.

It is well to bear in mind that the amount of opening movement of the gate structure is large because the opening in the bottom of the car should be large for quick and ready discharge and because with a large opening the side walls may be steep providing prompt discharge. However, in the described construction the dumping cam does not induce much shock or collision between the gate and cam because a gentle curve or warping can be employed on the cam and because the shock is absorbed within the cam, that is, the cam acts as a knife edge to pry the parts of the gate structure apart. 85 90

The construction and operation of the modification illustrated in Fig. 5 are as have been above described except that use is made of a single gate structure 12^a pivoted at 13 on an axis ranging in the direction of motion of the car, and use is made of one wedge cam structure 14 of the construction above described. 95 100

The construction and mode of operation of the modification illustrated in Fig. 6 are as above described except that use is made of one wedge cam structure 14 and of two gates 15 and 16 respectively pivoted on axes 17 and 18, ranging in the direction of motion of the car and geared together as at 19 so

that the cam 14, operating on the gate 15 through the gearing 19 operates the gate structure 16.

The construction and mode of operation of the modification shown in Fig. 7 are as above described except that the gate structure 20 is movable on rollers and a roller way 21 laterally of the tramway, and it is moved by a cam structure 22 of the type above described.

The construction and mode of operation of the modification shown in Fig. 8 are as above described except that there are a pair of roller gates 23 and 24 movable laterally of the tramway and there is a cam structure 25 substantially as shown in Figs. 3 and 4.

In Fig. 9 there is illustrated a tram car substantially the same as shown in Fig. 1 except that it is provided with a plurality of pairs of gates and with a plurality of openings for discharge. The cam structure employed with this multiple discharge tram car is substantially that shown in Figs. 3 and 4.

It will be obvious to those skilled in the art to which the invention relates that modifications may be made in details of construction and arrangement and in matters of mere form without departing from the spirit of the invention which is not limited to such matters or otherwise than as the prior art and the appended claims may require.

I claim:—

1. In tram car equipment the combination of a car provided with a dumping gate structure movable in a direction crosswise of the direction of motion of the car, and a dumping cam having its high part disposed at an angle to the perpendicular and adapted to operate said gate structure.

2. In tram car equipment the combination of a tramway, a car movable on the tramway

and having a dumping gate structure movable in a direction crosswise of the direction of motion of the car, and a dumping cam operative crosswise of the tramway and adapted to operate the gate structure.

3. In tram car equipment the combination of a car provided with a pair of self-closing dumping gates pivotally connected with the car on an axis ranging in the direction of motion of the car, and a cam of the general form of a parallelogram having wedge shaped ends and adapted to operate said gates.

4. In tram car equipment the combination of a tramway, a car movable on the tramway and having a pair of gates operable and closable in a direction crosswise of the tramway, and a cam of which the ends are disposed inwards and upwards in respect to the tramway and of which the middle portion is disposed above and generally parallel with the tramway.

5. In tram car equipment the combination of a tramway, a tram car having a self-closing gate structure openable and closable by movement crosswise of the direction of the tramway, and a wedge cam extending from the middle portion of the tramway laterally outwards and upwards into parallelism with the tramway and constituting means for positively opening said gate structure.

6. In tram car equipment a tramway, a laterally effective dumping cam having wedge shaped ends disposed generally centrally of the tramway, and a tram car having a self-closing gate structure laterally movable in respect to the tramway and adapted to be pried open and to be permitted to close by the wedge shaped portion of the cam.

ARTHUR WARNER
